Patented Aug. 6, 1918.

UNITED STATES PATENT OFFICE.

JOHN A. HELLSTROM, OF WHEELING, WEST VIRGINIA.

ANNEALING-BOX.

1,274,538.

Specification of Letters Patent. Patented Aug. 6, 1918.

Original application filed February 12, 1918, Serial No. 216,820. Divided and this application filed May 20, 1918. Serial No. 235,553.

To all whom it may concern:

Be it known that I, JOHN A. HELLSTROM, a subject of the Kingdom of Sweden, residing at Woodlawn, Wheeling, in the county of 5 Ohio and State of West Virginia, have invented certain new and useful Improvements in Annealing-Boxes, of which the following is a specification, reference being had therein to the accompanying drawing.

10 This invention relates to improvements in annealing boxes, and its object is to so construct the top, sides and ends of the box that the expansion and contraction thereof is so taken care of that cracking, buckling 15 and caving-in of the box is prevented under the severe heat to which it is subjected.

My improvement relates more particularly to what is usually termed "flat roof top" annealing box, but the improvement may be 20 utilized in connection with an "arch roof."

In the accompanying drawings—

Figure 1 is a side elevation showing an annealing box with my improved construction applied thereto.

25 Fig. 2 is an end elevation of Fig. 1.

Referring now to the drawings in which like characters represent the same parts, 1 is an elongated annealing box. Formed in the roof of this box are a plurality of 30 grooves 2, which are substantially U-shape in cross-section, and these grooves extend across the roof of the box and slightly down each side thereof, as shown. Located at each side of these U-shaped grooves 2, are 35 ribs 3, which extend parallel the grooves and form the side walls thereof, and the ribs like the grooves extend across the top of the box and slightly down its sides, as shown at 4. Connecting these transverse 40 ribs 3 are longitudinal ribs 5, and a central rib 6 extending longitudinal the roof from the end ribs 3, and partially down the ends of the box, as shown in Fig. 2.

The object of the U-shaped grooves 2 in 45 the roof, is to take care of the longitudinal expansion of the box, thereby preventing the roof from cracking, due to contraction, because the circular parts formed by the grooves 2 will naturally bend in both the 50 contraction and expansion.

The inverted sections formed by these 55 grooves 2 will also act as stiffeners for the roof, which will prevent the buckling or cracking of the roof, which often happens in the "flat roof" type of annealing boxes.

The ribs 3, 4, and 5 of the top of the box are placed at intervals and prevent any portion of the roof from buckling between the inverted sections 2, and owing to the fact that these ribs extend down somewhat on 60 the side of the box, they prevent the sides spreading at the top which is also often the case in boxes of the "flat roof" type.

The sides of the box are provided with a master oblong-shaped rib 7, and a second and smaller oblong shaped rib 8, embraced within the rib 7. Between the curved ends of the ribs 7 and 8, a curved rib 9 is located, and has its ends merged into the top and bottom of the rib 7. Curved ribs 10 70 are embraced within and between the curved ends of the rib 8 and a central rib 11. Connecting the curved ribs 7, 8, 9 and 10, and the central rib 11, is a centrally located and longitudinally extending rib 12, the ends of 75 this rib 12 extending beyond the master oblong rib 7. The ends of the box are provided with a large circular rib 13, and a smaller circular rib 14 embraced within the former circular rib. Radiating from these 80 ribs are the ribs 15, 16, 17, 18, 19, 20 and 21. These oblong, curved, and straight ribs on the sides and ends of the box, serve to take care of the longitudinal and cross-wise expansion and contraction, and owing to their 85 oblong shape they will move with the expansion and contraction of the box, and prevent it from cracking or buckling. These ribs also serve to straighten the sides and 90 ends of the box.

Referring again to the sides of the box, it will be noticed that the oblong and curved ribs 7, 8 and 9 are connected by outwardly radiating ribs 22, and that the lower radiating ribs 22 extend to the bottom of the box 95 and that ribs 23 radiate outward from the ends of the master oblong rib 7 to the edge of the box.

From the foregoing description, it will 100 be observed that the roof of the box is provided with a plurality of U-shaped transversely extending grooves, and that the edges of these grooves are formed by ribs, and that the top, sides and ends are provided with combined strengthening, expansion and contraction ribs, which prevent the box from cracking, buckling or caving-in under the action of the severe heat to which it is subjected.

Having thus described my invention, what 110

I claim and desire to secure by Letters Patent is:—

1. An annealing box formed as an integral structure having its top provided with a plurality of transversely extending U-shaped grooves, the edge walls of which are formed of ribs extending parallel to the said grooves to take care of the expansion and contraction of the top and prevent it from caving in.
2. An annealing box formed as an integral structure, having a flat top provided with a plurality of transversely extending U-shaped grooves, the edges of the grooves formed of ribs extending transverse the box and parallel the grooves, and ribs extending longitudinal the box between the curved ribs and connecting them, for the purpose described.
3. An annealing box formed as an integral structure having a top provided with a plurality of transversely extending U-shaped grooves, its ends and sides provided with curved and radiating ribs, for the purpose described.
4. An annealing box formed as an integral structure having its top provided with a plurality of transverse grooves having their edges formed of ribs, and its side provided with an oblong rib connected with the ribs of said grooves and its ends provided with circular ribs connected by a radiating rib, with the two end ribs of the grooves, for the purpose described.
5. An annealing box formed as an integral structure having its top provided with a plurality of U-shaped grooves, the edges of which are formed of ribs, the sides of the box provided with a plurality of oblong shaped ribs embracing curved ribs, the ends of the box provided with circular and radiating ribs, the parts combined for the purpose described.

In testimony whereof I hereunto affix my signature in the presence of two witnesses.

JOHN A. HELLSTROM.
